ROTATING HOOK.

Michael Joseph, Roslindale, Mass.

Application February 6, 1946; Serial No. 645,756

6 Claims. (Cl. 112—228)

1

The present invention relates to a sewing machine and more particularly to the rotating hook which serves to lock the thread brought through the cloth by the needle with the bobbin thread. In machines of the type to which the present invention applies, the rotating hook surrounds a bobbin on which the thread is wound and serves to carry the thread, brought through the cloth by the needle, around the bobbin in completing the stitch. The bobbin of the present arrangement is of the short disc type, and is held in a casing which itself is positioned in but free from the hook.

The hooks in the type of machine to which the present invention applies are subject to hard use since in each stitch the thread of the needle is hooked by the hook, the operation repeating many times a minute, particularly in high speed machines. As a result, the hook wears out and must be replaced and repaired. It is usual for repair men to substitute a new hook and send the old one back to the factory or shop for repair or to discard it entirely.

The present invention has for its aim a hook construction which can readily be repaired without any difficulty by the service or repair man. The invention may be applied to a type of hook in which the point of the hook is a permanent part of the hook or in which the point is renewable.

The present invention will be more fully understood upon reading the specification set forth below when taken in connection with the drawings annexed hereto illustrating the embodiments of the invention in which—

Figure 1 shows a view of the invention in elevation.

Figure 2 shows a plan view of the device of Figure 1.

Figure 3 shows a sectional view taken on the line 3—3 of Figure 2.

Figure 4 shows a perspective of a detail of Figure 1.

Figure 5 shows a modification of the invention in a position corresponding to Figure 1.

Figure 6 shows a plan view of the device of Figure 5.

Figure 7 shows a sectional view taken on the line 7—7 of Figure 6, and

Figure 8 shows a perspective of a detail of Figure 5.

In the form shown in Figures 1 to 4 inclusive, the body of the hook comprises a cut 1 with a short, hollow, cylindrical collar 2 formed at the bottom of the cup symmetrically positioned and extending outward thereof. This construction is commonly used and is necessary to fit into the standard sewing machine. At the open end of the cup there is a heavy ring 3 with an internal

2

seat 4. In the form shown in Figures 1 to 4 inclusive, a hook or point 5 is formed as a part of the ring 3. This hook or point at its end projects slightly upward and forward from the top or lip edge of the ring and is formed with an outwardly projecting edge 6 beneath which is an inward recession 7, all on the external side of the ring. The end 8 of the hook or point is the termination of the slot 9 which extends downward at an acute angle toward the base of the cup. The top surface of the ring 3 is cut lower than the point 8 of the hook adjacent the point so that the thread will be caught by the point 8 and pass down the slot 9 as the hook is rotated on an axis concentric with the cylindrical collar 2.

The above description applies to standard construction. In the further construction of the device shown in Figures 1 to 4 inclusive, the slot 9 in which the thread follows is provided with a guard or guide 10 which is spaced away from the recess 7 and is mounted in the outer surface of the ring 3.

For this purpose the ring 3 is recessed in its outer surface to the shape of the guard 10 so that when the guard 10 lies in the recess, its outer surface is flush and continuous with the cylindrical outer surface of the ring 3. The guard 10 is arcuate in shape with an upwardly extending portion 11 at one end terminating in an inwardly projecting short angle element 12 which fits over a portion of the top rim 13 of the cup. The bottom edge of the guard 10 is preferably level and the other end of the guard may be slightly enlarged, as indicated at 14, with a curve 15 which may parallel the slot 9. The enlarged end 14 is not as large at the end 11 and its upper edge, as seen in Figure 1, is below the edge of the lip of the ring 3 so that the recess in which the guard sets will hold the guard against any motion except falling outward. The guard 10 is held in the recess by two screws 16 and 17 in the large end 11 and one screw 18 in the smaller end of the guard threading into the ring 3.

The angle member 12 tapers at both ends of its top surface to the surface of the rim of the ring 3, thereby making a smooth surface for the lip of the cup.

In the operation of the machine, the point 8 of the hook comes between the needle and the thread and as the hook rotates, the thread is carried around the bobbin into the slot 9 and out again whereupon it is freed as the needle draws the thread upward. In one or both of these movements the thread rubs against the guard 10 which frequently wears and must be renewed. For this purpose the screws 16, 17 and 18 may be removed and a new guard substituted. The movement of the thread within the guard is limited by a pin 19 which is threaded 60 into the inner surface of the guard and preferably

adjustable by making a screw head slot 20 in the end of the threaded pin. The slotted end of the pin 19 engages a hole 21 through the ring 3 so that a complete bar is formed against the thread slipping past the normal recess 7 of the hook. This will prevent the thread from being caught between the surface of the ring 3 and the guard, if there is that tendency.

In the arrangement shown in Figures 5 to 8 inclusive, the construction of the hook is somewhat modified. Here the ring 30 is shaped as in Figure 1 except for the fact that the point is not carried up in the same way as in Figure 1. The point 32 is formed as a part of the band 31 (Figure 8) with a side portion 33 which comes against the ring 30 on the outside above the slot 34 and a top inwardly extending angle element 35 which lies over the edge of the rim of the ring. The band 31 is itself slotted at 36 to conform to the slot 34 in the body of the hook. Otherwise the band 31 may be the same as the band 16 with an enlarged end 37 having a hole whereby it is attached at one end to the body of the hook and an enlarged end section 38 having a lip 39 continuous with the element 35 extending over the top edge of the ring 30. A pin 40 may be similarly used corresponding to the pin 20 of Figure 4.

The point of the hook in the modification of Figures 5 to 8 is actually formed in the band but the top lip or flange 39—35, the side support 33 and the point 32 actually fit snugly against a similarly formed contour in the ring 30 of the hook and furnish support for the band.

A further improvement in the present invention is the method of attachment of the cap 41 over the shaft opening 42 at the base of the hook. The base 2 within the cup 1 is circularly grooved at 43 concentric with the hole 42 and the cap 41 has a downwardly extending flange 44 which sets in the groove. This is a forced fit and inserted in place before the base is machined.

It may be mentioned that the band 31 of Figures 5-8 is made flush with the outer surface of the hook by recessing the ring 30 in a contour so that the outer surface of the band will be flush with the surface of the ring similarly as explained in connection with Figures 1-5.

It will be noted that both bands or guards 10 and 31 may be changed without removal or adjustment of the hook as a whole and this adds greatly to the saving of time and convenience in repairs.

Having now described my invention, I claim:

1. In a rotating hook used in a sewing machine producing a lock stitch, the hook having a needle thread slot and a ring section at its rim with an externally recessed area in and extending below the ring adjacent the needle thread slot provided in the hook, an arcuate band closely fitting and spanning said externally recessed area, said band being disposed in said recessed area with its external surface flush with the surface of the ring on the outside thereof, said band having a flat lower edge and an upper edge with upwardly extending ends forming enlarged end sections, and screws set in said band and threading into said ring for holding said band in place in its enlarged end sections.

2. In a rotating hook used in a sewing machine producing a lock stitch, the hook having a needle thread slot and a ring section at its rim with an

externally recessed area in and extending below the ring adjacent the needle thread slot provided in the hook, an arcuate band spanning said externally recessed area, said band being disposed in said recessed area with its external surface flush with the surface of the ring on the outside thereof, said band having enlarged end sections with a flat lower edge, one end section being wider than the other and means passing through said end sections into said hook for clamping said band to said hook, the larger end section having an inwardly extending flange fitting flush over the rim edge of said ring.

3. In a rotating hook used in a sewing machine producing a lock stitch, the hook having a needle thread slot and a ring section at its rim with an externally recessed area in and extending below the ring adjacent the needle thread slot provided in the hook, an arcuate band spanning said externally recessed area, said band being disposed in said recessed area with its external surface flush with the surface of the ring on the outside thereof, said band having enlarged end sections with a flat lower edge, one end section being wider than the other and means passing through said end sections into said hook for clamping said band to said hook, the larger end section having an inwardly extending pin extending transversely across the recessed area into the surface of the hook.

4. In a rotating hook used in a sewing machine producing a lock stitch, the hook having a needle thread slot and a ring section at its rim with an externally recessed area in and extending below the ring adjacent the needle thread slot provided in the hook, an arcuate band spanning said externally recessed area, said band having a portion formed as an end of the hook with a flange extending over the rim of the ring and a side section fitting flush with the side of said ring.

5. In a rotating hook used in a sewing machine producing a lock stitch, the hook having a needle thread slot and a ring section at its rim with an externally recessed area in and extending below the ring adjacent the needle thread slot provided in the hook, an arcuate band spanning said externally recessed area, said band having enlarged ends recessed in the side of said ring, a portion of one of said enlarged ends being carried forward to form the point of said hook, said band having a slot, aligned with the slot in said hook.

6. In a rotating hook used in a sewing machine producing a lock stitch, the hook having a needle thread slot with a point formed on one side thereof, a removable band element spanning said slot and forming a covering shell over a portion of the hook, means securing said band to the side of said hook, the covering shell itself providing a point overlying and substantially covering the point of the hook.
